SAFETY LOCK

Constantine Juszczak, Chicago, Ill.

Application March 3, 1947, Serial No. 731,978

3 Claims. (Cl. 292—74)

1

This invention relates to improvements in safety locks for windows.

An object of the invention is to provide an improved safety lock for windows which will be positive in action when securing the window against movement, and will provide a resilient tensioning means between the window sash and the frame whereby the sash may be raised to any desired height and supported at the selected adjustment.

A further object of the invention is to provide an improved safety lock for window sashes which will include a housing mounted transversely upon the upper sash rail and will include a horizontally slidable locking pin which will be spring projected to engage an undulating track secured to the side of the window frame for holding the window in the desired adjusted open position, and a pivoted locking element adapted to be moved into locking position behind said pin when it is desired to secure the window against vertical movement in either direction.

A still further object of the invention is to provide an improved safety lock for windows which will be highly efficient in operation, and relatively inexpensive to manufacture and produce.

Other objects will appear as the description proceeds.

In the accompanying drawings which form a part of this application,

Figure 1 is a front elevation of the improved safety lock shown applied to a window sash and with the undulating locking strip shown secured to the adjacent base of the window frame;

Figure 2 is an edge view of the undulating locking strip;

Figure 3 is a front elevation of a portion of the undulating locking strip;

Figure 4 is a longitudinal sectional view taken through the improved safety lock showing the same in locked position, and showing the same in dotted lines with the locking catch in released position;

Figure 5 is a sectional view taken on the line 5—5 of Figure 4;

Figure 6 is a sectional view taken on the line 6—6 of Figure 4, and

Figure 7 is a sectional view taken on the line 7—7 of Figure 4.

Like characters of reference are used throughout the following specification and the accompanying drawings to designate corresponding parts.

In carrying out the invention, there is illustrated a window sash generally denoted by the

reference numeral 1, and a window frame 2 therefor.

5 A metal undulating locking strip 3 is securely fastened to the inside edge of the window frame 2 by means of the short screws 4 in position to be engaged by the improved safety lock hereinafter more fully described.

The safety lock is adapted to be secured upon the upper surface of the window sash 1, and comprises an elongated substantially rectangular shaped lock housing 5 formed by an upper plate 6 and a lower plate 7, together with the oppositely disposed side plates 8 and 9.

10 The oppositely disposed inwardly directed apertured ears 10 and 11 are formed integrally upon the opposite side plates 8 and 9 respectively, said apertures being threaded to receive the screws 12 which extend through threaded apertures formed through the upper plate 6 and through the lower plate 7, thereby supporting the upper and lower plate and the cooperating side plates in fixed position to provide a hollow elongated rectangular shaped housing.

15 A pair of spaced inverted U-shaped bearing ribs 13 are welded to the upper plate 6, while a pair of spaced U-shaped bearing ribs 14 are welded to the upper surface of the lower plate 7 directly below said ribs 13, forming guide channels for the elongated locking bolt 15, which is rectangular in cross section, and is reduced at its forward end to provide the finger 16.

20 Front and rear closure members 17 and 18 respectively are secured in the front and rear ends of the lock housing 5, and the front closure member 17 is centrally apertured to permit the forwardly extending cylindrical locking finger 16 to pass and slide therethrough to engage the undulating locking strip 3 secured to the adjacent side edge of the window frame 2. A stop lug 19 is formed integrally on the lower surface of the locking bolt 15, and is provided so that it will engage the adjacent U-shaped bearing rib 14 as the locking bolt is forced inwardly within the lock housing 5 to limit the inward movement thereof.

25 A stud 20 is fixed to the inner surface of the rear closure member 18 and supports one end of a substantially heavy coil spring 21, whose forward end is received within a bore 22 formed in the rear end of the said locking bolt 15, serving to normally and resiliently urge the said locking bolt 15 to its outermost position and into engagement with the metal undulating strip 3.

30 A bearing roller 23 is provided with reduced opposite ends 24 and 25, and is mounted transversely between the opposite side plates 8 and 9

of the lock housing 5, as clearly illustrated in Figure 5 of the drawings. A locking plate or member 26 is secured to the bearing roller 23 and is movable therewith, and supports the upwardly extending operating finger 27 which extends upwardly from the roller out through the longitudinal slot 28 formed through the rear end of the upper plate 6, whereby the locking plate or member 26 will be disposed behind the locking ear 29 formed integrally on the upper end of the locking bolt 15 and at the rear end thereof, thereby providing an absolute and positive lock for preventing the inward movement of the locking bolt for holding the same in positive contact with the undulating strip 3 secured to the inside surface of the window frame 2, thus preventing the window sash from being either raised or lowered.

When the operating finger 27 is moved rearwardly, the locking plate or member 26 will be disengaged from behind the locking ear 29 on the locking bolt 15 to release the bolt so that it will be free to slide backwardly and forwardly within the bearing ribs in said lock housing 5, for permitting the window sash to be raised or lowered if desired.

A pair of spaced downwardly extending lugs 30 are suitably secured to the undersurface of the upper plate 6 at the rear end thereof, and supports the leaf spring 31 therebetween, said spring being bowed downwardly to engage and rest on the upper surface of the bearing roller 23 to tension the operation of the same.

The lower plate 7 of the lock housing 5 will extend downwardly in the front end of said housing and at right angles thereto, being formed integrally therewith, and being provided with the apertures 33, through which securing screws (not shown) may be placed for locking the lock housing 5 in fixed position upon the top edge of the upper rail of the window sash 1.

From the foregoing description, it will be seen that the operation of the improved safety lock for sashes will be as follows: The operating finger 27 will be moved to the left, as viewed in Figure 4 of the drawings to release the locking bolt 15 so that the window sash 1 may be raised or lowered as desired, and when the window sash is to be locked in any position either part way up, or fully down, the operating finger 27 will be moved to a vertical position as shown in full lines in Figure 4, thereby moving the locking plate or member 26 behind the locking ear 29 formed on the locking bolt 15 to secure the same against movement and in locked position firmly and securely against the metal undulating strip 3 secured to the sash frame 2.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I

claim as new and desire to secure by Letters Patent of the United States is:

1. A sash fastener comprising an elongated casing adapted to be secured upon a window sash, oppositely disposed U-shaped bearing ribs on the inner surface of the top and bottom of the casing, a locking bolt slidably mounted in said ribs, a reduced locking finger on one end of the bolt, a central bore in the opposite end of the bolt, resilient means seated in said bore and abutting against one end of the casing for biasing said locking finger forwardly of the casing, a locking ear offset upwardly from the inner end of the bolt, a roller transversely journaled in the casing adjacent the inner end of the bolt, a locking plate carried by said roller engageable with said locking ear for holding the bolt in a fixed position, a finger lever secured to said roller and extending upwardly through the top of the casing for moving said locking plate into locking engagement with the ear and means for tensioning said locking plate.

2. The combination of claim 1, wherein said last-mentioned means includes a leaf spring secured to the under surface of the top of the casing and seated on the roller.

3. A sash fastener comprising an elongated casing adapted to be secured upon a window sash, oppositely disposed U-shaped bearing ribs on the inner surfaces of the top and bottom of the casing, a locking bolt slidably mounted in the bearing ribs, a reduced locking finger on one end of the bolt, a central bore in the opposite end of the bolt, a projecting stud on the adjacent end of the casing, a spring seated in said bore and received on the stud for biasing said locking finger forwardly of the casing, a stop lug depending from said bolt adjacent the locking finger and adapted to engage one of the U-shaped ribs for limiting inward movement of the locking finger, a locking ear offset vertically from the inner end of the bolt, a roller journaled transversely in the casing adjacent the inner end of the bolt, a locking plate fixed on the under surface of the roller, a finger lever secured to said roller and extending through the top of the casing for moving said locking plate into a horizontal position abutting the locking ear and holding the locking finger in an extended position, and resilient means for tensioning said locking plate.
